ADJUSTABLE WRENCH

Filed Oct. 10, 1927

Fig. 3.

Inventor
Edgar H. Bierly

By *Chasnow & Co*

Attorney

UNITED STATES PATENT OFFICE.

EDGAR H. BIERLY, OF EMPORIUM, PENNSYLVANIA.

ADJUSTABLE WRENCH.

Application filed October 10, 1927. Serial No. 225,285.

This invention has reference to wrenches and aims to provide novel means whereby a wrench when positioned on a nut, bolt or similar object, may be locked in such position, eliminating any possibility of the wrench slipping from the object under operation, while in use.

Another object of the invention is to provide a wrench of this character which will 10 be quick-acting and one which will be used in connection with objects of various sizes.

A still further object of the invention is to provide a wrench of this character which may be efficiently employed as an end wrench 15 or socket wrench at the will of the operator and without the necessity of making adjustments in the wrench construction.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed, without departing from the spirit of the invention.

Referring to the drawing:

Figure 1 is an elevational view of a 30 wrench constructed in accordance with the invention, the same being partly in section.

Figure 2 is a sectional view taken on line 2-2 of Figure 1.

Figure 3 is a sectional view taken on line 35 3-3 of Figure 1.

Figure 4 is a sectional view taken on line 4-4 of Figure 1.

Referring to the drawing in detail, the 40 device includes a pair of pivotally connected members 5 and 6 respectively, the members being provided with jaws 7 at their outer ends, while the inner ends thereof are formed into handles 8.

The section 5 has an enlarged portion 9 45 which is cut away providing a clearance for the member 6 that moves with respect thereto.

As shown, the members 5 and 6 have cut 50 out portions defining curved surfaces 10 that are engaged by the enlargement 11 eccentrically formed to provide a cam, to the end that when the enlargement 11 is moved or rotated to move over the curved surfaces 10 the members 5 and 6 will be 55 moved away from each other or permitted

to move towards each other according to the position of the enlargement 11.

The enlargement 11 is mounted on the pin 12 on which the lever 13 is mounted, which lever is pivotally mounted on the outer surface of the member 5 as clearly shown by Figure 1.

Teeth 14 are provided along one edge of the head 15 of the lever 13, which teeth are engaged by the pawl 16 that is pivotally supported on the member 5 so that when the lever 13 has been moved to a certain position, the pawl will operate to lock the lever 13 against movement.

As clearly shown by Figure 1, the jaws 7 70 have their outer surfaces curved as at 17 and are engaged by the sleeve 18 which is preferably rectangular in formation so that as the sleeve 18 is moved over the inclined surfaces 17, the jaws will be moved towards 75 each other, and when the jaws have been moved to a certain position, the sleeve will act to lock the jaws against movement.

This sleeve 18 is moved when the lever 13 is moved, the connection between the sleeve 80 and lever 13 being made through the link 19 that is eccentrically connected with the head of the lever. It should be obvious that when the jaws 7 are moved into clamping 85 relation with an object to be positioned by the wrench, the lever 13 will act to move the sleeve 18 to lock the jaws against movement as described.

In order that the wrench may be used as a socket wrench, a bar 20 is pivotally connected with the member 5 and is provided with a cut away portion 21 into which the member 6 extends, the member 6 contacting with the walls of the cut away portion so that by rotating the member 10 the 95 wrench may be turned when positioned as a socket wrench.

A rectangular head 22 is provided on the bar 20 so that the head may be engaged by an end wrench for rotating the wrench after 100 it has been positioned.

From the foregoing it will be seen that when it is desired to position the wrench, the lever 13 is moved so that the jaws 7 are separated, whereupon the lever is moved 105 in the opposite direction causing the cam 11 to separate the handles of the members 5 and 6, resulting in the jaws 7 being moved into close engagement with the object under operation.

With this movement of the lever to close the jaws on the object under treatment, the sleeve 18 moves to lock the jaws in such position and in such a way as to prevent the 5 jaws from slipping from their work.

I claim:

1. A wrench including pivoted members, 10 jaws at the outer ends of the pivoted members and handles at the inner ends thereof, said jaws having their outer surfaces curved, a cam disposed between the handles for moving the handles away from each other to close the jaws, a lever for operating the cam, a sleeve movable over the curved 15 surfaces of the jaws to lock the jaws against

movement, and a link connecting the lever and sleeve to move the sleeve simultaneously with the movement of the cam.

2. A wrench including pivoted members, 20 said pivoted members having handles, said handles having curved surfaces, jaws at the outer ends of the pivoted members, a pivoted cam disposed between the handles and co-operating with the curved surfaces to move the handles away from each other to close 25 the jaws, and a lever for operating the cam.

In testimony that I claim the foregoing as my own, I have hereto affixed my signature.

EDGAR H. BIERLY
